(57) **CLAIM**

I claim the ornamental design for footwear, as shown and described.

DESCRIPTION

FIG. 1 is a front perspective view of footwear, showing my new design;

FIG. 2 is a right side view thereof; and,

FIG. 3 is a back perspective view thereof.

The broken lines are included for illustrating environmental structure and form no part of the claimed design.

1 Claim, 3 Drawing Sheets*FIG. 1*

FIG. 2

FIG. 3
